DESIGN FOR A COMB

Crofton C. Holden, Leominster, Mass., assignor to Tilton & Cook Co., Leominster, Mass., a corporation of Massachusetts

Application March 23, 1946, Serial No. 127,860

Term of patent 14 years

(Cl. D86—8)

To all whom it may concern:

Be it known that I, Crofton C. Holden, a subject of the King of Great Britain, residing at Leominster, in the county of Worcester and Commonwealth of Massachusetts, have invented a new, original, and ornamental Design for a Comb,
of which the following is a specification, reference being had to the accompanying drawings,
forming a part thereof.

In the accompanying drawings Fig. 1 is a plan view of a comb showing my new design, Fig. 2 is a front view of the comb shown in Fig. 1, and
Fig. 3 is a sectional view on line 3—3 of Fig. 2.

Shading on the drawing has been omitted in part for convenience in illustration.

I claim:

The ornamental design for a comb, substantially as shown and described.

CROFTON C. HOLDEN.
